PIN UP VANITY CASE HOLDER

Carmine Charles Di Stiso, Waterbury, Conn.

Application December 4, 1944, Serial No. 566,627

7 Claims.

(Cl. 63—2)

1

This invention relates to costume jewelry, and more particularly to a detachable holder for a vanity case having means for pinning it upon a woman's wearing apparel.

One object of the invention is to provide a composite holder and vanity case which will blend together in an artistic and decorative manner.

A further object is to provide an article of the above nature which may be detachably pinned upon any desired part of a woman's external ensemble.

A further object is to provide a composite article of jewelry of the above nature which will facilitate the use of a vanity case, avoid the necessity of carrying it in the hand or in a pocketbook, and will prevent it from becoming mislaid.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing:

Fig. 1 represents a perspective view of the composite holder and vanity case as it appears in assembled position and pinned to the wearing apparel of the user.

Fig. 2 is a transverse sectional view of the same, taken along the line 2—2 of Fig. 1, looking downwardly.

Fig. 3 is a top plan view of the empty holder by itself.

Fig. 4 is a longitudinal sectional view of the same.

Fig. 5 is a longitudinal sectional view of the assembled vanity case and holder.

In the present day fashions of women's dress, it is well-known that there is no convenient place for carrying vanity cases or other articles of this type, and therefore, one purpose of the present invention is to provide a simple and effective holder for a vanity case, which holder may be pinned to the wearing apparel in such a manner as to permit the vanity case to be easily removed therefrom.

Referring now to the drawing in which like reference numerals denote corresponding parts throughout the several views, the numeral 10 indicates an attachment pin having a rounded knob 11 at one end, and a tapered point 12 at the other end. In order to hold the pin securely in position,

2

it is provided adjacent the point 12 with a short threaded section 13, and the pin is adapted to penetrate the wearing apparel 14 at two points 14a, 14b in the manner shown in Figs. 1 and 2.

The pin 10 also is attached to a depending rectangular holder 15 which has on its upper end a pair of rearwardly-extending lugs 16, 17. The lug 16 is drilled throughout its length, while the lug 17 is drilled at the outer half of its length, and is tapped with interior screw threads 17a for the remaining inner half of the length thereof.

In order to frictionally hold a vanity case 26 detachably within the rectangular holder 15, provision is made of a pair of V-shaped resilient 15 staggered locking leaf springs 18, 19 which are preferably soldered or cemented to the horizontal top and bottom walls 20, 21 of the holder.

The holder 15 also has vertical side walls 22, 23 provided with finger notches 24, 25, which permit the vanity case 26 to be readily removed by the fingers of one hand. The vanity case 26 has flat top and bottom ends 26a, 26b, and a front face 27 provided with an ornamental design 28, and when assembled, the vanity case 26 will have its rear face 29 in contact with the base 30 of the holder 15 while the ornamental front face 27 of said vanity case will be substantially flush with the forward edges of the holder 15, as shown in Figs. 1, 2, and 5.

Operation

In the operation of the present invention, when it is desired to attach the vanity case holder 15 to the wearing apparel 14, it will merely be necessary to pass the pin fastener 10 through the rear lug 16, and then push the point 12 through the wearing apparel 14 at the two points 14a, 14b, as clearly shown in Fig. 2. The point 12 of the pin 10 will then be inserted into the aperture in the lug 17 as far as it will go. The knob 11 will then be twisted, causing the threaded section 13 to be screwed into the tapped section 17a of the lug 17 until the pin 10 reaches the position shown in Figs. 1 and 2.

The holder 15 will then be ready to receive the vanity case 26 which will be manually inserted within the top and bottom walls 20, 21 and the side walls 22, 23, as far as it will go, until it engages the base 30 of the holder.

While there has been disclosed in this specification one form in which the invention may be embodied, it is to be understood that this form is shown for the purpose of illustration only, and that the invention is not to be limited to the specific disclosure, but may be modified and em-

bodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an article of jewelry, a holder of rectangular shape having a pair of rearwardly-extending lugs at the upper end thereof, a pointed attaching pin passing through said lugs to detachably secure said holder to an article of wearing apparel through which said pin is passed, a vanity case shaped to loosely fit within said holder, and inwardly-extending means on the inner walls of said holder for detachably holding said vanity case in position.

2. The invention as defined in claim 1, in which said pin is provided with a threaded section located a short distance from the point thereof, and in which one of the lugs of said holder is provided with a tapped section to cooperate with said threaded section for locking said pin in attaching position.

3. The invention as defined in claim 1, in which a pair of V-shaped leaf springs are secured to the upper and lower end walls of said holder for detachably engaging said vanity case when it is pressed rearwardly into position in said holder.

4. The invention as defined in claim 1, in which one of said lugs has an aperture tapped for only a portion of its length, and the other lug has an

aperture drilled throughout its length to permit the free passage of the attaching pin therethrough.

5. In an article of jewelry, a holder of rectangular shape having a pair of rearwardly-extending lugs at the upper end thereof, a pointed attaching pin passing through said lugs to detachably secure said holder to an article of wearing apparel through which said pin is passed, a vanity case shaped to loosely fit within said holder, and inwardly-extending means on the inner walls of said holder for detachably holding said vanity case in position, said pin having an enlarged lug-engaging knob on the end opposite from its point.

6. The invention as defined in claim 1, in which a pair of staggered V-shaped leaf springs are soldered to the upper and lower end walls of said holder for detachably engaging said vanity case when it is pressed rearwardly into position in said holder.

7. In an article of jewelry, a holder having a pair of rearwardly-extending lugs at the upper end thereof, a pointed attaching pin connected to said lugs to detachably secure said holder to an article of wearing apparel through which said pin is passed, a vanity case shaped to loosely fit within said holder, and inwardly-extending means on the inner walls of said holder for detachably holding said vanity case in position.
